DESIGN FOR A FRUIT JUICE EXTRACTOR OR THE LIKE

Raymond Zurawin, New York, N. Y.

Application May 20, 1939, Serial No. 85,100

Term of patent 14 years

To all whom it may concern:

Be it known that I, Raymond Zurawin, a citizen of the Polish Republic, having declared my intention of becoming a citizen of the United States, residing in New York, in the county of the Bronx and State of New York, have invented a new, original, and ornamental Design for a Fruit Juice Extractor or the like, of which the following is a specification, reference being had to the accompanying drawing, forming part thereof.

The figure is a perspective view of a fruit juice

extractor or the like which embodies my new design.

The side of the extractor which is not shown has substantially the same appearance as that illustrated.

The dominant features of my design reside in the portions shown in full lines.

I claim:

The ornamental design for a fruit juice extractor or the like, as shown and described.

RAYMOND ZURAWIN.
